(57) **CLAIM**

The ornamental design for a pipe end refacing tool, as shown and described.

DESCRIPTION

FIG. 1 is a perspective view of a pipe end refacing tool according to the present invention;

FIG. 2 is a right elevational view thereof, the left side being a mirror image;

FIG. 3 is a top plan view thereof, the bottom being a mirror image;

FIG. 4 is a front elevational view thereof; and,

FIG. 5 is a back elevational view thereof.

The broken lines showing environment in the drawings are included for illustrative purposes only and form no part of the claimed design.
